(57) **CLAIM**

The ornamental design for a vehicle tail light, as shown and described.

DESCRIPTION

FIG. 1 is a rear elevational view of a vehicle tail light showing our new design;

FIG. 2 is a perspective view thereof;

FIG. 3 is a side elevational view thereof.

FIG. 4 is a rear elevational view of the left-handed version thereof;

FIG. 5 is a side elevational view of the left-handed version thereof; and,

FIG. 6 is a perspective view of the left-handed version thereof.

The broken line showing of the remainder of the vehicle rear end is for illustrative purposes only and forms no part of the claimed invention. The vehicle tail light illustrated in FIGS. 1-3 is right-handed, and FIGS. 4-6 illustrate the left-handed version of the light having the same design.
